INLAID SURFACE FOR WINDOW SILLS

Werner B. Anderson, Detroit, Mich., assignor to
Detroit Steel Products Company, Detroit, Mich.,
a corporation of Michigan

Application May 8, 1950, Serial No. 160,779

3 Claims. (Cl. 189—75)

1

The present invention relates to a window construction and more particularly to one in which a special member is inlaid into a surface of a window sill.

Modern window constructions often include window frame elements including a relatively wide sill member extending into the room from the sash or sash frame. Where this sill is formed of steel, even though painted, there is a tendency for it to corrode due to water which may come through an open ventilator, or which may result from condensation at the room side of the ventilator. According to the present invention the sill member of the casing is provided with an inlaid member formed of linoleum, asphalt tile, or other corrosion resistant material. The inlaid member not only prevents corrosion of the casing sill but also provides an attractive appearance. If desired, the inlaid member may simulate marble or the like.

It is an object of the present invention to provide in a window construction, a sill member having secured thereto a separate inlaid member formed of corrosion resistant material.

It is a further object of the present invention to provide a sill member having an upstanding flange along its room side edge and provided with a corrosion resistant inlaid member abutting the flange along one edge.

It is a further object of the present invention to provide a window construction comprising a sill member having an upstanding flange along its room side edge and a sash frame bar adjacent its weather side edge in combination with a jamb construction, the lower edge of which engages the surface of the sill member and form, together with the flange and sash frame bar, side walls of a recessed seat at the upper surface of the sill member, in which a corrosion resistant inlaid member is provided.

Other objects and features of the invention will become apparent as the description proceeds, especially, when taken in conjunction with the accompanying drawings, wherein:

Figure 1 is a perspective view of a window construction incorporating the present invention.

Figure 2 is a fragmentary section on the line 2—2, Figure 1.

Figure 3 is a fragmentary section on the line 3—3, Figure 1.

Figure 4 is a fragmentary vertical section illustrating the manner in which the casing sill and casing jamb members interfit.

Figure 5 is a perspective view of a window to which the invention is applied.

Figure 6 is an enlarged section on the line 6—6, Figure 5.

Figure 7 is a fragmentary vertical section of a modification of the sill shown in Figure 1.

2

Figure 8 is a view similar to Figure 7 showing a modified construction.

Referring now to the drawings, the invention is illustrated as applied to a casement type window construction. The window opening in the wall is framed by a casing construction including a sill member 10, jamb members 12, and a top or head casing member 14. Mounted within the opening framed by the casing members 10, 12, and 14, is a ventilator frame including a sash frame sill bar 16, vertical sash frame bars 18, and head bars (not shown). Within the sash frame are mounted swinging ventilators 20.

Referring now to Figure 4 the casing sill member 10 is formed of sheet metal, preferably steel, and includes an upstanding flange indicated generally at 22, at its room side edge, which extends above the relatively depressed portion 23 of the sill member. Below the flange 22 the casing sill 10 includes a depending portion 24 and an inturned portion 26 which is adapted to serve as a plaster stop as best illustrated in Figure 2. The flange 22 includes an inclined wall 28 for a purpose which will presently appear. The casing sill 10 cooperates with the jamb members 12 as best seen in Figure 4. For this purpose the jamb members 12 are of less width than the sill member by an amount substantially equal to the width of the flange 22. The lower edge of the jamb members 12 abut against the upper surface of the depressed portion 23 of the sill member and are interlocked therewith by tabs 30 which extend through correspondingly positioned slots provided in the sill member and which are thereafter bent over as indicated in Figures 2 and 3.

Adjacent its weather side edge the sill casing 10 has secured thereto the sash frame sill bar 16. Therefore the depressed portion 23 of the casing sill member is surrounded at the room side by the flange 22, at the ends by the casing jamb members 12, and at the weather side by the sash frame sill bar 16. These members together define a recessed seat located at the upper surface of the casing sill member.

This seat is provided with a corrosion resistant inlaid member 32. Preferably, the inlaid member is formed of a separate sheet material such for example as linoleum, asphalt tile, or the like. If desired, it may be in the form of a suitable plastic or non-ferrous material either initially formed into a sheet material and precut to fit within the recessed seat, or applied thereto in plastic form and allowed to harden or set therein.

In practice, excellent results are obtained when the inlaid member is formed of linoleum. In order to retain the inlaid member in position, suitable adhesive is provided which is coextensive with the bottom and edge surfaces of the member and which not only retains the member firmly in the illustrated position, but which also serves

to prevent the entrance of water at the edges of the member. The edge of the member 32 along the room side thereof may be beveled to cooperate with the inclined wall 28 of the flange 22, thus providing a firm mechanical interlock to retain 5 the member in position.

In many cases it is desirable to ship the casing members and sash frame members disassembled and to assemble them into the casing frame and the sash frame on the job. Where this is done 10 it is of course desirable to first assemble the sash frame sill bar 16 to the casing sill member 10, after which the member 32 is adhesively applied to the casing sill member. Application of the member 32 to the casing sill member 10 may take 15 place either before or after assembly of the casing sill member 10 with the casing jamb members 12.

Referring now to Figures 5-8 there is illustrated additional modifications of the same invention. 20 As seen in Figures 5 and 6, the window construction comprises a broad sill 40 having a portion 42 extending outwardly beyond the room side wall surface 44. The window opening in this case is illustrated as provided with the plaster return type construction, the corner 46, the window opening surface 48, and the wall surface 44 being 25 plaster when casement type windows 50 are provided. The sill member 40 is formed of metal and the portion which extends into the room beyond the inner surface of the wall 44 is formed to provide an upwardly extending portion such as a bead or flange 52, beyond which there is a broad flat surface 54. The casement window 50 in this instance is illustrated as adapted to 30 weather directly against the weather side of the sill frame bars 56. The broad flat surface 54 of the sill is covered with an inlaid sheet member which may be of corrosion resistant material such for example as linoleum or the like as previously 35 described. The room side edge of the sheet member abuts and partially underlies an inclined inner surface of the bead or flange 52 in the same manner as shown in Figure 2.

In Figure 7 there is illustrated a modification 40 of the sill illustrated in Figure 1. In this case the sill member 60 includes an upstanding bead 61 extending into the room beyond the plaster 45 62. Toward the weather side of the sill member 60 there is a broad flat depressed portion 63 which receives the sheet member 64 formed of 50 corrosion resistant material. In this construction the sill member 60 at its weather side is formed to cooperate with and provide a surface against which the ventilator sill bar 65 weathers. 55 It will be appreciated that in this construction the jamb and head members which cooperate with the sill member to encase the window opening, are similarly formed to cooperate with the corresponding jamb and head members of the 60 ventilator frame.

Referring now to Figure 8 a somewhat modified construction is provided. In this case the sill member in addition to an upstanding flange or bead 70, at its room side, is provided with a similar upstanding flange 72 adjacent its weather side against which the sill bar 74 of the ventilator 76 is adapted to weather. The flange or bead 70 and the flange 72 together define side walls of a 70 depressed central portion 78 of the sill member 78 which is completely covered by the inlaid corrosion resistant sheet member 80.

In cases where the sides of the window open-

ing are closed by the plaster return type of construction the sill member may if desired be provided with an inlaid sheet member such as 80 which extends under the plaster. Alternatively, the inlaid sheet member may be applied after the plaster has been finished in which case it will abut the finished plaster at its ends.

The plaster return type of construction has been specifically illustrated but it will be readily appreciated that the invention is equally applicable to other types of window constructions such for example as where a wood casing is applied to surround the sides and top of the window opening.

The essential feature of the invention is in the provision of a sill member formed of metal and having a depressed seat in which is provided a corrosion resistant sheet material adapted to provide a finish surface for the sill. The metal sill is constructed and arranged to protect the inlaid material and to provide an attractive appearance for the assembly.

The drawings and the foregoing specification constitute a description of the improved inlaid surface for a window sill in such full, clear, concise and exact terms as to enable any person skilled in the art to practice the invention, the scope of which is indicated by the appended claims.

What I claim as my invention is:

1. In a window construction having spaced vertical jamb surfaces at opposite sides of a window opening and a ventilator at the weather side of the opening, a window sill formed of sheet metal and extending inwardly from the ventilator beyond the room side edge of said jamb surfaces, the room side edge of said sill being formed into an upwardly extending bead the weather side edge of which is substantially in the plane of the room side edge of said jamb surfaces, a corrosion resistant sheet member adhered to the flat upper surface of said sill and abutting said bead and covering substantially the entire surface of said sill between said bead and the ventilator, and between the jamb surfaces.

2. Structure as defined in claim 1 in which said sill has an upwardly extending flange at the weather side thereof against which the weather side edge of said sheet member abuts.

3. A window frame construction comprising a broad sill member having an upstanding narrow flange along its room side edge, jamb members having inner surfaces at the bottom thereof intersecting the upper surfaces of said sill member at the ends thereof and at the weather side of said flange, an upwardly extending elongated element extending along said sill at the weather side thereof, said flange, the inner surfaces at the bottom of said jamb members, and said element defining a completely surrounded recessed seat on said sill member, and a corrosion resistant sheet member covering said entire seat and adhered thereto.

WERNER B. ANDERSON.
